Primary Examiner — Darlington Ly(74) *Attorney, Agent, or Firm* — Andrew Morabito(57) **CLAIM**

The ornamental design for a motorcycle body, as shown and described.

DESCRIPTION

FIG. 1 is a top, front, and right side perspective view of a motorcycle body showing my new design;

FIG. 2 is a left side elevation view thereof;

FIG. 3 is a top plan view thereof;

FIG. 4 is a front elevation view thereof;

FIG. 5 is a rear elevation view thereof; and,

FIG. 6 is a left side elevation view thereof when installed on an exemplary motorcycle.

The broken line showing of the motorcycle engine, motorcycle frame, and other elements of the motorcycle are for the purposes of illustrating environmental structures and do not form part of the claimed design.
